UNITED STATES PATENT OFFICE.

FRANK. M. GODFREY, OF CONGDON, NEBRASKA.

VISUAL ELECTRIC SIGNAL.

SPECIFICATION forming part of Letters Patent No. 310,412, dated January 6, 1885.

Application filed April 10, 1884. (No model.)

To all whom it may concern:

Be it known that I, FRANK. M. GODFREY, of Congdon, county of Dawson, and State of Nebraska, have invented a new and useful Improvement in Visual Electric Signals; and I do hereby declare that the following is a full, clear, and exact description of the invention, which will enable others skilled in the art to which it appertains to make and use it, reference being had to the accompanying drawings, forming a part thereof.

My invention relates to improvements in railroad-signals in which an electrical detent works in conjunction with a current-breaker; and the object of my invention is to provide a signal to work when an accident occurs. I attain this object by the means shown in the accompanying drawings, in which—

Figure 1 is a perspective view of a railroad-bridge having my invention applied. Fig. 2 is a detail of my signal-box. Fig. 3 is the armature-bearing reflector. Fig. 4 is the circuit-breaker.

Similar letters refer to corresponding parts in all the views.

A A is a bridge, to which the signal-wires are attached by means of the insulators B B, into which the wires are so placed, as shown in Fig. 4, as to allow them to be pulled out when any of the parts to which the insulators are attached are broken. The wire is carried backward and forward and zigzagged across the bridge, and fastened with the insulators B B, and then along the road by means of the ordinary telegraph poles, to the signal-boxes C C, which are located a good distance on both sides from the bridge. In the boxes C C is an electric magnet or detent having suspended therefrom a reflector the concavity of which is turned away from the bridge, so that at night the light from the head-light of the engine is

reflected back and enables the engineer to see whether the reflector is up or down, or whether any accident has occurred on the bridge ahead. From the box the wire is run back to a station 45 and connected with a battery, or is connected close at hand. E is the armature or detent, and E' the reflector attached thereto. F is the wire connecting the bridge, signal-magnets, and main line. When the bridge breaks, the 50 wires in the insulators are pulled apart and at once break the circuit, thereby neutralizing the magnets in the boxes C C, and thereby allowing the reflector to fall, and thus signal.

Of course my invention does not relate strictly to bridges, but may be laid along the track in a wooded country, or in a deep cut where an avalanche is likely to occur, so that anything falling across the track will break 60 the wire and cause the effect described above.

Having thus fully described my invention, what I claim, and desire to secure by Letters Patent of the United States, is—

1. The combination of the magnet D, armature E and reflector E' attached thereto, at a signal-box, and electrical connections to a bridge or other part crossed by the road, substantially as and for the purpose set forth. 65

2. The combination of the magnet D, armature E and reflector E' attached thereto, at a signal-box, with electrical connections, as described, to road and line, and the insulators B B upon the bridge or other part of road, substantially as and for the purpose set forth. 75

In testimony that I claim the foregoing I append my signature.

FRANK. M. GODFREY.
